(57) **CLAIM**

The ornamental design for a segmented tailgate LED strip, as shown and described.

DESCRIPTION

FIG. 1 is a front elevational view of a two-segment tailgate LED strip.

1 Claim, 5 Drawing Sheets

FIG. 2 is a rear elevational view of the two-segment tailgate LED strip.

FIG. 3 is a top plan view of the two-segment tailgate LED strip.

FIG. 4 is a bottom plan view of the two-segment tailgate LED strip.

FIG. 5 is an enlarged right side elevational view of each segment comprising the two-segment tailgate LED strip. The left side elevational view being a mirror image thereof.

FIG. 6 is a front elevational view of a three-segment tailgate LED strip.

FIG. 7 is a rear elevational view of the three-segment tailgate LED strip.

FIG. 8 is a top plan view of the three-segment tailgate LED strip.

FIG. 9 is a bottom plan view of the three-segment tailgate LED strip.

FIG. 10 is an enlarged right side elevational view of each segment comprising the three-segment tailgate LED strip. The right side elevational view being a mirror image thereof; and,

FIG. 11 is a perspective view of a truck having attached a segmented tailgate LED strip. The truck as well as the strip's electrical connections are shown in broken lines for environmental purposes only and form no part of the claimed design.
